J. B. JONES.

RIFLE CLEANING ROD,

APPLICATION FILED FEB. 9, 1920.

1,347,381.

Patented July 20, 1920.

UNITED STATES PATENT OFFICE.

JOHN BERTRAND JONES, OF BROOKVILLE, PENNSYLVANIA.

RIFLE-CLEANING ROD.

1,347,381.

Specification of Letters Patent. Patented July 20, 1920.

Application filed February 9, 1920. Serial No. 357,151.

To all whom it may concern:

Be it known that I, JOHN BERTRAND JONES, a citizen of the United States, residing at Brookville, in the county of Jefferson 5 and State of Pennsylvania, have invented certain new and useful Improvements in Rifle-Cleaning Rods, of which the following is a specification, reference being had to the accompanying drawings.

10 This invention relates to rod-like devices for cleaning guns and rifles or to other devices of this character, and particularly to foldable or collapsible rods.

15 The general object of my invention is to provide a device of this character which is formed in two or more jointed sections and which is adapted to be folded up into a small compass so that it may be readily carried.

20 And a further object is to provide a device of this character which, when the rod is unfolded and the joints disposed in alinement with each other, the several sections of the rod are rigidly connected to each 25 other so that the rod is strong and rigid in use.

Other objects will appear in the course of the following description.

My invention is illustrated in the accompanying drawings, wherein:—

Figure 1 is a side elevation of my improved gun cleaner;

Fig. 2 is a like view to Fig. 1, but showing the outer sleeve 18 in section;

Fig. 3 is a like view to Fig. 2, but showing the two sections of the rod folded upon each other;

Fig. 4 is a fragmentary sectional view of the sleeve 20 showing the joint between the

40 sections 10 and 11.

Referring to these drawings, it will be seen that my rifle cleaning rod consists, as illustrated, of two main sections 10 and 11. These sections are jointedly connected to 45 each other by a link 12. The adjacent ends of the sections 10 and 11 are bifurcated and the links disposed in said bifurcated ends and pivoted to the bifurcated ends by pivots 13. The outer end of the section 10 is 50 screw-threaded, as at 14, and carries a removable nut 15 at its outer end, and disposed inward of this nut is an interiorly screw-threaded head 16 formed at its outer end with a recess 17 to receive the nut 15.

55 Disposed on the section 10 is a slidable sleeve 18. The section 11 at its outer end

is screw-threaded for engagement with a terminal portion 19 which, at its junction with the rod, is larger in diameter than the rod, and disposed loosely around the rod 60 is a sleeve 20 which is knurled, roughened or otherwise formed upon its exterior, as at 21, so that it may be readily grasped between the thumb and fingers of the hand. This sleeve is formed with longitudinally 65 extending slots 22 at opposite points in its diameter, these slots opening at the outer end of the sleeve, and a transverse pin 23 passes through the section 11 and is adapted to pass into these slots. The extremity of 70 the sleeve 20 is formed between the slots 22 with notches 24 extending a slight distance into the sleeve.

In the use of this device, assuming it to be folded so as to bring the sections 10 and 75 11 into parallel relation, the sections are unfolded and disposed in alinement with each other. Then the sleeve 20 is shifted along the section 11 until the pins 23 escape from the slots 22. Then the sleeve is rotated so as to engage these pins 23 with the notches 24. This will carry the sleeve 20 entirely over the link 12, and this sleeve will, therefore, hold the two sections 10 and 11 in alinement with each other. In 80 order to hold the sleeve 20 in this position against accidental detachment, the sleeve 18 is abutted against the sleeve 20 and then the head 16 turned down until it abuts against the end of the sleeve 18. In this position 90 the parts are locked in place against any accidental detachment and the rod is rigid. Of course, the terminal end 19 may be so formed as to itself wipe out or otherwise clean the gun, or it may be formed to carry 95 a wiping rag, or various tools may be applied to the screw-threaded extremity of the section 11. When it is desired to fold up the rod, the head 16 is unscrewed as far as possible. Then the sleeve 18 is slipped 100 back upon the section 10, which permits the section 20 to be shifted sufficiently far to release the pin 23 from engagement with the notches 24, and then the sleeve 20 is turned to bring the slots 22 in alinement with the 105 pin, which permits the sleeve 20 to be shifted along the section 11 until it uncovers the link 12. Under these circumstances, the two sections 10 and 11 may be folded into parallel relation, as shown in 110 Fig. 3.

While I have illustrated a construction of

this character in which the rod is formed in two sections, it will be obvious that the rod might be formed in more than two sections, the sections being jointed to each other by links 12, and these links being held each by a sleeve 20. I do not wish to be limited to the use of this device as a rod for cleaning or wiping guns, as it is obvious that the principle of the device 10 might be applied to various other articles.

As above stated, this device might be formed in a plurality of sections, and ordinarily it will be formed in three sections. The hinging axis of each section, however, 15 will be at right angles to the hinging axis of an adjacent section or the other section in order to permit the rod to be folded up into a small compass. Modern high power rifles usually have a 22" barrel or a 24" 20 barrel. Therefore, the two sections of the wiping rod, where only two sections are used, would be from 12" to 14" in length when closed.

1 claim:—

25 1. An implement of the character described including two sections pivotally connected to each other whereby the sections may be turned into parallel relation or into alinement, a longitudinally slotted sleeve 30 mounted upon one of said sections, said section having a transverse pin engageable with the slots of the sleeve, the slots of the sleeve being open at one end and the sleeve being provided with notches in its end between said 35 slots with which said pin is adapted to engage, and means for releasably locking the sleeve in position with its notches in engagement with the pin to thereby hold the sleeve from longitudinal shifting movement and 40 over the joint between the sections.

2. An implement of the character described including two sections, a link pivoted to the adjacent ends of the two sections and connecting these sections and permitting the 45 sections to be turned into or out of parallel relation, and means for holding the two sections in extended relation comprising a sleeve on one of said sections shiftable into position entirely over the link and engaging both of 50 said sections or into a position to entirely uncover the link, and screw threaded means for locking the sleeve in the first named position.

3. An implement of the character described including two rod sections, a link pivotally connected to the adjacent ends of the rod sections whereby the rod sections 55 may be turned into or out of parallel relation, a longitudinally slotted sleeve mounted upon one of said sections, said section having a transverse pin engageable with the slots of the sleeve, the slots of the sleeve being open at one end and the sleeve being provided with notches in its end between said slots 60 with which said pin is adapted to engage, a second sleeve mounted upon the other sec- 65

tion and slidable therealong to abut against the first named sleeve, and a screw-threaded head mounted on the second named section and adjustable into or out of abutting engagement with the second named sleeve. 70

4. An implement of the character described including two rod sections, a link pivotally connected to the adjacent ends of the rod sections whereby the rod sections may be turned into or out of parallel relation, a longitudinally slotted sleeve mounted upon one of said sections, said section having a transverse pin engageable with the slots of the sleeve, the slots of the sleeve being open at one end and the sleeve being provided with notches in its end between said 75 slots with which said pin is adapted to engage, a second sleeve mounted upon the other section and slidable therealong to abut against the first named sleeve, a nut on the extremity of the second named section, and a head having screw-threaded engagement with the second named section between said nut and the end of the sleeve mounted on the second named section, the head being adapted to be shifted to engage the second named sleeve and hold the sleeves locked over the joint between said sections. 80

5. An implement of the character described including a rod formed of two sections, both of said sections at their adjacent ends being bifurcated, a link pivoted to the bifurcated ends of the sleeve, and flexibly connecting them to each other, one of said sections being screw-threaded at its extremity and provided with a terminal detachably engaging this extremity, a sleeve mounted upon said first named section and having slots extending longitudinally from one end of the sleeve, pins on the first named section with which said slots are adapted to engage, this end of the sleeve being formed with notches between said slots with which said pins are adapted to engage, said sleeve when shifted to bring the pin into engagement with said notches extending over the link and engaging the other rod section to thereby hold the rod sections in alinement, a second named sleeve mounted upon the last named rod section for sliding movement, and a screw-threaded head engageable with the outer end of the second named rod section and movable into or out of abutting engagement with the end of the sleeve mounted on said rod section. 105 110 115

6. An implement of the character described including two sections, a link pivoted to the adjacent ends of the two sections and connecting these sections and permitting the sections to be turned into or out of parallel 120 relation, and means for holding the two sections in extended relation comprising a sleeve on one of said sections shiftable into a position entirely over the link and engaging both of said sections or into a position to 125 130

entirely uncover the link, said sleeve having a longitudinally extending slot and a notch extending parallel to the slot, the section having a pin extending into said slot and engageable with said notch, and means for holding the sleeve with the notch engaging said pin to thereby prevent a rotation of

the sleeve to bring the pin into alignment with the slot and permit longitudinal movement of the sleeve on the section.

10

In testimony whereof I hereunto affix my signature.

JOHN BERTRAND JONES.
